(57) **CLAIM**

The ornamental design for fluid distribution equipment, as shown and described.

DESCRIPTION

1. Fluid distribution equipment

FIG. 1.1 is a side elevation view of a fluid distribution equipment, showing my new design;

FIG. 1.2 is front elevation view thereof;

FIG. 1.3 is a front perspective view thereof;

FIG. 1.4 is another perspective view thereof;

A metal cylinder is enclosed by a housing; the cylinder is visible through windows in the housing.
